AIR PURIFIER

William C. Hartzell, Union Beach, N. J.

Application December 28, 1935, Serial No. 56,559

9 Claims. (Cl. 183—35)

This invention relates to a mechanical air purifier and has for an object to provide an improved means for mechanically purifying the air in a room or enclosed space and at the same time for causing a circulation of the air.

A further object of this invention is to provide a device for removing silica, dust, lint, pollen, bacteria or other harmful impurities from the atmosphere or air especially when used in occupational places such as offices, hospitals, residences, trains, busses as well as underground in mining operations and the like.

Yet a further object of the invention is to provide an air purifier that is portable, inexpensive to operate and comparatively inexpensive to manufacture and assemble.

An additional object of this invention is to provide an air purifier that will cut down such occupational diseases as silicosis or miner's consumption or other diseases caused by the presence of harmful mining or manufactured debris entering the atmosphere during the mining or manufacturing process.

As an additional feature this invention comprises a small portable unit including a pair of twin propellers operated by a single motor the first of which propellers will turn to suck air through a comparatively coarse purifier and the second of which will then flow this partially purified air through a comparatively fine purifier. The purifying element is so shaped and supported as to provide a large area of cleaning surface.

With the foregoing and other objects in view as will hereafter become apparent, this invention comprises a construction, combination and arrangement of parts hereinafter set forth, disclosed and shown on the accompanying drawings.

In the drawings:

Figure 1 is a vertical sectional view of the air purifier of this invention.

Fig. 2 is an elevational view of one of the purifier elements.

Fig. 3 is an elevational view of one of the purifier elements wire supports, and

Fig. 4 is an enlarged view on line 4—4 of Fig. 2 showing one of the spring supports forming part of the wire supports.

There is shown at 10 the air purifier of this invention. This air purifier 10 includes a housing 11 mounted on a plurality of telescopically adjustable legs 12 and 13, the legs 12 and 13 being supported in extensions 14 and 15 and held fixed relative thereto by means of set screws 16 and 17, so that both the elevation and angle of the hous-

ing 11 may be adjusted as desired. Additional brace members 18 may be provided to reinforce the legs as necessary, it being observed that the legs 12 and 13 are each provided in pairs or in greater numbers as may be necessary.

Supported within the housing 11 by means of rods 19 is an electric motor 20 having a motor shaft 21 extending through both ends thereof. Fastened to each end of the motor shaft 21 is an airplane type propeller 22, the tips 23 of the propeller 22 extending into circumferential grooves 24 for the length of the propellers 22 is slightly larger than the diameter of the housing 11. As the motor 20 is operated from any suitable source of electricity, the propellers are rotated so as to draw air in the direction of the arrows 25 through the air purifier housing 11. The housing 11 is in the form of an open-ended cylinder. An air purifying element such as shown in Figs. 2, 3 and 4 is mounted at each end of the cylindrical housing 11. The air purifier elements 26 and 27 are substantially identical in construction except for the back as the purifier element 27 is somewhat finer than the elements 26, so that the elements 26 will take out the coarse particles while the elements 27 will take the finer particles, bacteria, germs and the like from the air as it passes therethrough.

Each of the elements 26 and 27 are honeycombed in shape as shown and are provided with a plurality of cells 28. A wire grid 29 is provided as a support for each of the purifier elements 26 and 27. The wire grid 29 with its purifier elements is detachably mounted in the cylinder so that it may be removed for cleaning purposes whenever necessary. The wire grid 29 consists of a wire ring 30 to which are secured a plurality of criss-crossing wires 31 and 32. Secured to the grid, are a plurality of conical-shaped springs 33, the springs 33 corresponding in number to the number of the cells 28 formed in the honeycomb air purifier element so that as shown in Fig. 4, as well as in Fig. 1, a spring 33 extends between each of the cone-shaped honeycomb cells 28 and thus serves to support and reinforce the purifying elements 26 and 27.

As will be seen from the drawings, the purifier elements 26 and 27 are disc shaped in form with the frusto-cone shaped cells or cups extending therefrom in the direction of the airflow. The discs are sufficiently stiff to support and hold these against the inside of the ends of the housing. When there is no pressure of air flowing through the housing the springs 33 do not exert

any pressure against the air purifier disc but when there is pressure of air flowing therefrom the springs 33 yieldably resist the tendency of the disc to belly in the direction of airflow and thus hold them in proper operative position.

Grease nipples 34 are connected by conduits 35 to the motor shaft bearings so that the same may be lubricated when necessary without disassembling the purifier 10.

10 In operation the purifying elements 26 and 27 are supported against the wire springs 33 and the wire grid 29 and mounted at each end of the housing 11, as shown in Fig. 1. The purifying elements 26 and 27 will be made of porous rubber, spun glass or any other suitable or well known material which will serve the purpose of removing impurities from the air as it is passed therethrough. The elements 27 will be made of a finer mesh or density than that of the elements 15 26, so that the air as it passes through the elements 26 will first have the coarser particles of lint, dust and debris removed therefrom and then as it is drawn by the propellers 22 on through the housing it will be forced against the purifier elements 27 to remove the finer particles 20 therefrom and thereby clean the air. The purifier 10 may be mounted in any suitable or convenient location. In the home it would preferably be mounted near an open window. In an occupational place it would preferably be mounted wherever there are dust creating conditions such as operating machinery, mining operations 25 and the like.

The novel features and the operation of this 30 device will be apparent from the foregoing description. While the device has been shown in the structure described in detail, it is obvious that this invention is not to be considered limited to the exact form disclosed and that changes may 35 be made therein within the scope of the invention.

Having thus set forth and disclosed the nature of this invention, what is claimed is:

1. An air purifier comprising an open-ended 40 housing, an air purifier element mounted at one end of the housing, an air purifier element mounted at the other end of the housing, and means in said housing for sucking air through one of said air purifier elements and for forcing 45 the air through the other of said purifying elements, said means comprising a motor, a motor shaft extending therethrough longitudinally of the housing and a propeller mounted at each end of said motor shaft.

50 2. An air purifier comprising an open-ended housing, an air purifier element mounted at one end of the housing, an air purifier element mounted at the other end of the housing, means in said housing for sucking air through one of said air purifier elements and for forcing the air through the other end of said purifying elements, said means comprising a motor, a motor shaft extending therethrough longitudinally of the housing and a propeller mounted at each end of 55 said motor shaft, the purifier elements through which the air is forced being of a finer grade than the elements through which the air is sucked.

60 3. An air purifier comprising an open-ended cylindrical housing, a purifier element mounted at each end of said housing, a motor within said housing, a motor shaft extending through opposite ends of said motor, and an airplane type propeller mounted on each end of said motor

shaft, one of said propellers serving to suck air through one of said air purifier elements, and the other of said propellers serving to force air through the other said purifier elements.

4. An air purifier comprising an open-ended 5 cylindrical housing, a purifier element mounted at each end of said housing, a motor within said housing, a motor shaft extending through opposite ends of said motor, an airplane type propeller mounted on each end of said motor 10 shaft, one of said propellers serving to suck air through one of said air purifier elements and the other of said propellers serving to force air through the other of said purifier elements, the length of said airplane type propellers being 15 slightly greater than the average diameter of said cylindrical shaped housing, and grooves formed in said housing to receive the tips of the propellers.

5. An air purifier comprising a housing, means 20 for forcing air through said housing and a honeycomb shaped air purifier element mounted on said housing, said element being an integral disc having a plurality of frusto-cone shaped portions pressed therefrom and extending in the 25 direction of the flow of air.

6. An air purifier comprising a housing, means 30 for forcing air through said housing and a honeycomb shaped air purifier element mounted on said housing, said element being an integral 35 disc having a plurality of frusto-cone shaped portions pressed therefrom and extending in the direction of the flow of air, and means for supporting said honeycomb shaped purifier element in said housing.

7. An air purifier comprising a housing, means 40 for forcing air through said housing and a honeycomb shaped air purifier element mounted on said housing, means for supporting said honeycomb shaped purifier element in said housing, said supporting means comprising a wire 45 grid and a plurality of cone-shaped springs mounted on said grid and resting against said purifier elements between the cells thereof.

8. An air purifier comprising a cylindrical 50 shaped housing, means for supporting said housing, an electric motor supported within said housing, a shaft extending through the opposite ends of said motor, an airplane type propeller mounted on each end of said shaft within said 55 housing, circumferential grooves formed in said housing and receiving the airplane type propellers therein, a coarse grained purifier element mounted in said housing at one end thereof, and a fine-grained purifier element mounted in said housing at the other end thereof.

9. An air purifier comprising a cylindrical shaped housing, means for supporting said housing, an electric motor supported within said housing, a shaft extending through the opposite ends of said motor, an airplane type propeller mounted on each end of said shaft within said 60 housing, circumferential grooves formed in said housing and receiving the airplane type propellers therein, a coarse grained purifier element mounted in said housing at one end thereof, a fine grained purifier element mounted in said housing at the other end thereof, each air purifier element including a honeycomb cell shaped 65 disk, a wire grid and a plurality of springs supported on said wire grid and resting against said disk member and between the cells.
